SIGNAL LAMP

Jeremiah D. Kennelly, 408 S. Oak Park Ave.,
Oak Park, Ill.

Filed Feb. 8, 1965, Ser. No. 83,725

Term of patent 14 years

(Cl. D72—1)

FIG. 1

FIG. 2

FIG. 3

FIG. 4

FIG. 1 is a front elevational view of a signal lamp, showing my new design;

FIG. 2 is a rear elevational view thereof;

FIG. 3 is a top plan view thereof; and

FIG. 4 is a side elevational view thereof.

I claim:

The ornamental design for a signal lamp, as shown.
